UNITED STATES PATENT OFFICE.

CHARLES G. HILL, OF NOTTINGHAM, ENGLAND.

DESIGN FOR RUFFLING.

SPECIFICATION forming part of Design No. 21,260, dated December 22, 1891.

Application filed November 30, 1891. Serial No. 413,598. Term of patent 3½ years.

To all whom it may concern:

Be it known that I, CHARLES GREY HILL, a subject of the Queen of Great Britain, residing at Nottingham, in the county of Nottingham, England, have invented and produced a new and original Design for Ruffling, of which the following is a specification, reference being had to the accompanying drawings, forming part thereof, in which—

10 Figure 1 is a front elevation of the ruffling embodying the features of the design, and Fig. 2 is a rear elevation thereof.

15 The principal feature of the design consists of the irregular ornamental figures A, arranged in longitudinal grouping, covering and appearing to extend above the edge of body figure B, simulating a strip of fabric. The ornaments A are located diagonally upon the body figure in contact with each other,

concealing the edge of the body when the 20 latter is viewed from the front. The ornaments A, viewed separately in front elevation, are essentially conical in general contour, and appear to curl at their upper ends and to stand out from the body at their lower ends. 25 When viewed collectively, a spiral or wave-like effect is obtained. When the ornaments are viewed from the back, a decided spiral effect is visible, as a pronounced loop-like figure is located at their upper ends. 30

I claim—

A design for ruffling, substantially as herein shown and described.

C. G. HILL.
